UNITED STATES PATENT OFFICE.

FRANK E. WATERMAN, OF PARKERSBURG, WEST VIRGINIA.

FOUNTAIN-PEN.

No. 909,262.

Specification of Letters Patent.

Patented Jan. 12, 1909.

Application filed April 2, 1908. Serial No. 424,716.

To all whom it may concern:

Be it known that I, FRANK E. WATERMAN, a citizen of the United States, residing at Parkersburg, in the county of Wood and 5 State of West Virginia, have invented new and useful Improvements in Fountain-Pens, of which the following is a specification.

This invention relates to certain new and useful improvements in fountain pens and 10 the object thereof is to provide a pen of such class in the manner as hereinafter set forth, whereby the flow of ink to the pen point can be regulated as well as shut off entirely when occasion so requires and when shut off will 15 prevent leakage of ink, whether the pen is carried on the person or laid upon a desk or other support.

A further object of the invention is to 20 provide a fountain pen which shall be simple in its construction, strong, durable, efficient in its use, will provide a continuous and even flow of ink to the pen point when in use, inexpensive to manufacture, and having the parts so set up and arranged as to enable the 25 ready cleaning thereof when occasion so requires.

With the foregoing and other objects in view, the invention consists in the novel construction, combination and arrangement 30 of parts as hereinafter specifically described and illustrated in the accompanying drawings, wherein is shown the preferred embodiment of a fountain pen in accordance with this invention, but it is understood that 35 changes, variations and modifications can be resorted to which come within the scope of the claims hereunto appended.

In the drawings:—Figure 1 is a vertical 40 sectional view of a fountain pen in accordance with this invention when not in position to be used. Fig. 2 is a sectional elevation of the fountain pen when in position to be used. Fig. 3 is a perspective view of the body portion of the pen which constitutes 45 the ink reservoir, and Fig. 4 is a view looking towards one end of said body portion.

Referring to the drawings by reference 50 characters, 5 denotes the body portion of the pen which is cylindrical in contour and hollowed out as at 6 to constitute a reservoir. The lower end of the body portion is closed as at 7 with the exception of a plurality of outlet channels 8 formed in the end 7. The upper 55 end of the reservoir 6 is closed through the medium of a cap 9 provided with interior threads engaging with exterior threads

formed on the body portion 5. The body portion 5 at its upper end is cut away to provide a shoulder 10 against which abuts the lower end of the cap 9. The diameter of the 60 cap 9 with respect to the diameter of the body portion 5 is such that the cap 9 will form a continuation of the said body portion. The latter is further provided at its lower end with a depending annular extension 11 65 provided with exterior screw threads and said annular extension 11 is of less diameter than the diameter of the body portion 5 and is formed integral with the end 7 of the body portion at a point removed from 70 the peripheral edge of said body portion 5. Formed integral with the end 7 of the body portion 5 and depending therefrom is a conical-shaped extension 12 formed with 75 peripheral threads and said extension 12 is positioned approximately centrally of the outer face of the lower end 7 of the body portion 5. The diameter of the conical extension 12 at its upper end is such as to cause 80 said end to terminate between the outlet channels 8. The conical extension 12 constitutes a valve for regulating the flow of ink to the pen point and for shutting off the flow of ink and in connection with the annular extension 11 constitutes means whereby leakage 85 is prevented when the conical extension 12 is moved to a position to shut off the flow of ink in a manner as hereinafter set forth to the pen point. The conical extension 12 is further provided with one or more grooves 13 90 at its lower end to facilitate the supply of ink to the pen point.

The reference character 14 denotes a pen point coupling member and is provided at its upper end with an annular groove 15 with 95 one wall thereof screw-threaded and the said annular groove 15 is adapted to receive the annular extension 11 whereby the coupling member 14 is connected with the body portion 5. The coupling member 14 at its upper 100 end is furthermore provided with a conical-shaped opening 16 which has the wall thereof screw-threaded and is adapted to be engaged by the valve 12. The wall of the opening 16 forms a seat for the valve 12 105 when the latter is moved to closing position. The wall of the opening 16 is furthermore provided with a groove 17 to facilitate the flow of ink to the pen point. The lower portion of the coupling member 14 is 110 formed with a socket 18 which is adapted to receive the pen point 19. Secured in the

coupling member 14 and projecting under and upon the pen point 19 is a conducting tube 20 the upper end of which communicates with a passage 21 formed in the member 14 and opening into the lower end of the conical-shaped opening 16. The upper end of the member 14 is formed with an upwardly extending annular collar 22 adapted to receive the lower end of the body portion 5.

10 The pen further comprises a cap member 23 adapted to engage the coupling member 14 to inclose the pen point, as clearly shown in Fig. 1, when the pen is not in use, and adapted to embrace the body portion 5, as 15 clearly shown in Fig. 2 when the pen is adapted for use.

The height of the conical-shaped opening 16 with respect to the length of the valve 12 is such that when the valve 12 is seated, as 20 clearly shown in Fig. 1 whereby the supply of ink is shut off to the pen, an ink receiving chamber 24 will be provided, the walls of which are formed by the top edge of the member 14, the inner face of the flange 11, 25 the lower face of the end 7 and the periphery of the valve 12. When the pen is to be used and the flow of ink is desired, the body portion is turned to shift the threads of the valve 12 out of engagement with the threads 30 formed in the wall of the opening 16. This action elevates the body portion 5 and increases the area of the chamber 24, as clearly shown in Fig. 2. When the valve 12 is in the position shown in Fig. 2 a passage is 35 formed therebetween and the wall of the opening 16 and owing to such arrangement the ink will then flow to the pen point as will be evident, the grooves 13 and 17 facilitating the flow of ink. By the construction set up 40 the flow of ink can be regulated and in this connection it will be stated that the width of the passage formed between the valve 12 and the wall of the opening 16 can be increased or diminished as desired, depending on the 45 extent the valve 12 is removed from the opening 16. When the valve is seated it prevents the flow of ink to the pen point and the flange 11 prevents leakage from the chamber 24.

50 Although the adaptation of the invention is shown in connection with a fountain pen, yet it is evident it can be utilized in connection with a stylographic or other form of pen embodying a reservoir. The coupling member 14 can have that extremity carrying the pen point so modified as to be readily adapted for a pen of the stylographic class, as it is evident that the invention does not reside in the pen point, but in that part of the pen 55 which regulates the flow of ink from the reservoir to the writing point of the pen.

What I claim is:—

1. A fountain pen comprising a hollow body portion constituting an ink reservoir 65 and provided with an outlet, said body por-

tion having extending from one end a conical screw-threaded valve and an annular screw-threaded extension, combined with a coupling member carrying a pen point and provided with an annular groove having the wall 70 thereof screw-threaded adapted to receive said annular flange and further provided with a conical-shaped opening having the wall thereof screw-threaded and adapted to be engaged by the screw-threaded valve 75 whereby the flow of ink to the pen point is shut off.

2. A fountain pen comprising a hollow body portion constituting an ink reservoir and provided with an outlet, said body portion having extending from one end a conical screw-threaded valve and an annular screw-threaded flange, combined with a coupling member carrying a pen point and provided with an annular groove having the wall there- 80 of screw-threaded and adapted to receive said annular flange and further provided with a conical-shaped opening having the wall thereof screw-threaded and adapted to be engaged by the screw-threaded valve 85 whereby the flow of ink to the pen point is shut off, said valve formed with a groove to facilitate the flow of ink to the pen point when the valve is removed from its seat.

3. A fountain pen comprising a body por- 90 tion and a pen point coupling member connected thereto, said coupling member provided with a screw-threaded opening and further having means communicating with said opening for conducting ink to the pen 95 point, said body portion hollowed out to constitute an ink reservoir and further provided at one end with a screw-threaded extension constituting a valve and adapted to engage the wall of said opening whereby the flow of 100 ink can be shut off, said screw-threaded extension further constituting means for regulating the flow of ink to the pen point, and said extension furthermore provided with a 105 groove to facilitate the flow of ink to the pen 110 point.

4. A fountain pen comprising a body por- 115 tion and a pen point coupling member adjustably connected to the body portion, said body portion hollowed out to constitute an ink reservoir and further provided with an outlet for said reservoir, said coupling member having a screw-threaded opening and said coupling member further provided with means communicating with said open- 120 ing for supplying ink to the pen point, and said body portion provided with a screw-threaded extension adapted to engage the screw-threaded wall of said opening whereby the flow of ink can be shut off, said screw-threaded extension further constituting means for regulating the flow of ink to the pen 125 point and provided with a groove to facilitate the passage of the ink towards the pen point.

5. A fountain pen comprising a body por- 130

- tion and a pen point coupling member adjustably connected to the body portion, said body portion hollowed out to constitute an ink reservoir and further provided with an outlet for said reservoir, said coupling member having a screw-threaded opening and said coupling member further provided with means communicating with said opening for supplying ink to the pen point, and said body portion provided with a screw-threaded extension adapted to engage the screw-threaded wall of said opening whereby the flow of ink can be shut off, said screw-threaded extension further constituting means for regulating the flow of ink to the pen, said extension in connection with the body portion and the coupling member forming an ink receiving chamber with which said outlet communicates.
6. A fountain pen comprising a body portion and a pen point coupling member adjustably connected to the body portion, said body portion hollowed out to constitute an ink reservoir and further provided with an outlet for said reservoir, said coupling member having a screw-threaded opening and said coupling member further provided with means communicating with said opening for supplying ink to the pen point, and said body portion provided with a screw-threaded extension adapted to engage the screw-threaded wall of said opening whereby the flow of ink can be shut off, said screw-
- threaded extension further constituting means for regulating the flow of ink to the pen and provided with a groove to facilitate the passage of the ink towards the pen point, said extension in connection with the body portion and coupling member forming an ink receiving chamber with which said outlet communicates.
7. A fountain pen comprising a hollow body portion constituting an ink reservoir and provided with an outlet, said body portion having projecting from one end a conical screw-threaded valve and an annular screw-threaded extension, combined with a coupling member carrying a writing point and provided with an annular groove having the wall thereof screw-threaded and adapted to receive said annular extension, said coupling member further provided with a conical-shaped opening and having the walls screw-threaded and adapted to be engaged by the screw-threaded valve whereby the flow of ink to the writing point is shut off, said screw-threaded extension surrounding said valve.
- In testimony whereof I have hereunto set my hand in presence of two subscribing witnesses.
